UNITED STATES PATENT OFFICE.

JOHN T. TRUMBLE, OF FLINT, MICHIGAN, ASSIGNOR OF ONE-HALF TO A. B. C. HARDY,
OF FLINT, MICHIGAN.

PUMP.

1,161,999.

Specification of Letters Patent. Patented Nov. 30, 1915.

Application filed April 8, 1914. Serial No. 830,329.

To all whom it may concern:

Be it known that I, JOHN T. TRUMBLE, a citizen of the United States of America, residing at Flint, in the county of Genesee, and State of Michigan, have invented certain new and useful Improvements in Pumps, of which the following is a specification, reference being had therein to the accompanying drawings.

10 This invention relates to pumps especially designed for supplying gasolene or other liquid fuel to the carburetor of an internal combustion engine.

The primary object of my invention is 15 to provide an automatic pump that can be advantageously used in connection with the engine of an automobile for pumping gasolene from a tank or reservoir located at a point below the carburetor of the engine 20 to an elevation from which the gasolene can flow by gravity to the carburetor, the pump having an auxiliary reservoir into which gasolene is pumped or drawn by the suction in the intake manifold of the engine.

25 Another object of my invention is to provide a gasolene pump that is intermittently operated and automatically controlled, whereby at all times a sufficient quantity of gasolene is maintained in the auxiliary 30 tank or reservoir of the pump to supply the carburetor.

A further object of this invention is to establish a connection between a gasolene tank and the intake manifold of an internal combustion engine whereby the suction in the 35 manifold can be utilized for drawing gasolene into an auxiliary tank or reservoir interposed in the connection at a point above the carburetor of the engine, and then utilizing a float mechanism for controlling the 40 operation of the pump and consequently the supply of gasolene to the auxiliary tank or reservoir.

With the above and other objects in view 45 the invention resides in the novel construction, combination and arrangement of parts to be hereinafter specifically described and then claimed.

Reference will now be had to the drawings 50 wherein—

Figure 1 is a diagrammatic view of an automobile showing a liquid fuel supply arrangement including the improved pump,

and Fig. 2 is a vertical sectional view of a pump in accordance with this invention. 55

The pump comprises a circular base 1 having a bracket 2 by means of which the base may be connected to the dash 3 of an automobile 54. The dash 3 constitutes a suitable support and the base 1 is maintained at 60 right angles thereto or in a horizontal position. The base 1 has an upstanding annular flange 4 and a depending annular flange 5. Brazed or otherwise secured to the flange 5 and abutting the base 1 are the upper 65 edges of a cup-shaped auxiliary tank or reservoir 6, which has the bottom thereof provided with an opening 7 and a connection 8 for the coupling 9 of a carburetor tube or pipe 10, which communicates with 70 a carburetor 50.

The base 1 has a central opening or openings 11, a spider 12, and a depending hollow member 13 that extends into the auxiliary tank or reservoir 6 and is provided with an 75 angularly disposed or upwardly directed outlet nipple 14. The outer end of the nipple 14 has a transverse slot 15 and a seat 16 for a check valve 17. The check valve 17 is in the form of a ball or spherical body 80 and is retained within the nipple 14 by a cotter pin 18 or other fastening means arranged transversely of the nipple. The nipple 14 and the pin 18 constitute a cage for the check valve and permit of said valve 85 unseating to allow gasolene to flow from the hollow member 13 into the auxiliary tank or reservoir 6.

Seated upon the base 1 and brazed or otherwise secured to the upstanding flange 90 4 is a vertically disposed pump cylinder 19 having the upper end thereof provided with a peripheral flange 20 that is secured by screw bolts 21 and nuts 22 to a circular cap 23. The cap 23 has a bracket 24 suitably 95 secured to the dash 3, whereby said cap and the base 1 coöperate in supporting the pump relatively to the dash or a suitable support. To establish a non-leakable connection between the flange 20 and the cap 23 a gasket 100 25 is interposed between the flange and the cap.

The cap 23 is provided with a concentric stem 26 having a side connection 27 for the coupling 28 of a tube or pipe 29 in communication with an intake manifold 51 of an in-

ternal combustion engine. The stem 26 and the side connection 27 have an angle port 30 and the vertical portion 31 of said port is in communication with a vertical guide opening 32 for a float rod 33. The upper end of the rod 33 extends through a recess 34 in the top of the stem 26 and said recess communicates with the pump cylinder 19 through the medium of a port 35. The port 35 and the recess 34 are adapted to place the pump cylinder 19 in communication with the atmosphere, and the upper or outer end of the rod 33 has a cap or valvular member 36 adapted to seat upon the stem 26 and close the outer end of the recess 34. The valvular member 36 is adapted to close by gravity and be raised by the action of a float to be hereinafter referred to. When the valvular member is seated to exclude air from the cylinder 19, it is impossible for gasolene to flow from the cylinder into the reservoir 6, but immediately upon the valvular member being raised, the gasolene can open the check valve 17 and enter the reservoir. The valvular member 36 is suitably secured to the upper end of the rod 33 and suitably connected to the upper end of the stem 26 is a cap 37 having a small opening 38. The cap 37 is adapted to prevent dirt and foreign matter from entering the recess 34 and eventually reaching the pump cylinder 19. The lower end of the float rod 33 extends through and is guided by the spider 42 and keyed or otherwise detachably mounted upon said rod, contiguous to the lower end thereof, is a collar 39. The collar is adapted to support a hollow cylindrical float 40 arranged in the pump cylinder 19, said float having a central tube 41 through which the rod 33 extends. The float 40 is of a less diameter than the cylinder 19 and is limited in its upward movement relatively to the rod 33 by a sleeve 42 keyed or otherwise mounted upon said rod.

The sleeve 42 has the ends thereof provided with peripheral flanges 43 and 44, the former serving as a stop for the float 40 and the latter as a valvular member adapted to engage the inner side of the cap 23 and seal or close the inner end of the vertical portion 31 of the angle port 30. The flange or valvular member, however, does not close the port 35 to the atmosphere, but simply controls the communication between the manifold 51 and the cylinder 19. It is necessary for the valvular member to close the port 30, otherwise, with the cylinder taking air, the manifold would pull from the atmosphere and it would be impossible to reduce the pressure in the cylinder to that extent that gasolene would flow therein from the main reservoir 52, which is some distance from the pump and in a lower plane.

The cap 23, adjacent to the bracket 24,

has a connection 45 for the coupling 46 of 65 a tube or pipe 47 connected to a main tank or reservoir 52 of the automobile.

The base 1, adjacent to the bracket 2 thereof, has an angularly disposed port 48 establishing communication between the auxiliary 70 tank or reservoir 6, and a stand pipe 49 supported by the bracket 2 in parallelism with the pump cylinder 19. The upper end of the stand pipe 49 is open and permits of gaso- 75 len or liquid fuel flowing from the auxiliary tank or reservoir 6 into the carbureter pipe 10, when the check valve 17 is seated or closed.

As illustrated by full lines, the valvular member 36 is seated upon the upper end of 80 the stem 26, shutting off the connection to the atmosphere, and supporting the float rod 33 in a lowered position in the pump cylinder 19. By reason of gasolene or liquid fuel having been removed from the auxiliary tank or reservoir 6 and consequently the level of gasolene lowered within the pump cylinder 19, the float 40 rests upon the collar 39, and with the rod 33 in a lowered position, the valvular member 44 of the sleeve 85 42 is unseated, thereby establishing communication between the pump cylinder 19 and the manifold pipe 29. With the port 35 closed to the atmosphere it is possible for the suction in the intake manifold of an internal combustion engine to pump or draw gasolene from the main tank through the tank pipe 47 into the pump cylinder 19. As gasolene is drawn into the pump cylinder 19, the float 40 is gradually raised and contacts 90 with the flange 43 of the sleeve 42. The sleeve 42 and the rod 33 are then elevated until the valvular member 44 contacts with the cap 23 and seals or closes the vertical portion 31 of the angle port 30, thereby shutting off the connection between the pump cylinder 19 and the manifold pipe 29. The float mechanism assumes a position shown by 95 dot and dash lines and in such position the valvular member 36 is unseated, thereby 100 placing the pump cylinder 19 in communication with the atmosphere. The check valve 17 can then be unseated to permit of gasolene flowing from the pump cylinder 19 into the auxiliary tank or reservoir 6, and as 105 heretofore stated, the gasolene can readily flow from the auxiliary tank or reservoir 6 by reason of the stand pipe 49 communicating with the atmosphere.

It is apparent from the above that the 110 suction or vacuum within the pump cylinder tends to hold the valvular member 36 seated during the operation of the pump and that the unseating of this member and the seating of the member formed by the flange 44 115 120 is quickly performed by reason of the vacuum within the pump cylinder resisting the pressure of gasolene below the float until

- the pressure upon the float is greater than that of the vacuum, at which time there is a snap or rapid movement of the rod 33, which unseats the member 36 and closes the port 31.
- 5 The size of the auxiliary tank or reservoir 6 and the pump cylinder 19 is such that the supply of gasoline therein only necessitates intermittent operation of the pump, which is automatically controlled by the float mechanism within the pump.

10 During the operation of the pump, should gasoline vapor be drawn through the pipe 29 into the intake manifold of an internal combustion engine, this vapor tends to enrich the explosive mixture drawn from the carburetor, consequently the efficiency of an engine would be materially increased by the installation of the pump, besides the main gasoline tank or reservoir can be conveniently located upon the chassis or in the body of an automobile.

15 From the foregoing it will be observed that a sufficient quantity of gasoline is maintained within the auxiliary tank or reservoir 6 to supply a carburetor during the operation of the pump and that the check valve 17 or a similar automatic closure is essential to shut off communication between the pump cylinder 19 and the auxiliary tank or reservoir during the pulling or drawing of gasoline into the pump cylinder by the suction produced in the intake manifold of an internal combustion engine. Furthermore, a float actuated valvular member 42 controls 20 the operation of the pump and a similarly actuated valvular member 36 controls the flow of gasoline from the pump cylinder to the auxiliary tank or reservoir.

25 By reference to Fig. 2 it will be observed that the rod 33 constitutes an axial connection between the valvular members 42 and 36 and a simple means of simultaneously moving said members in the axis of the cylinder 19. The rod 33 obviates a plurality of 30 connections and devices and would undoubtedly be necessary, if the ports 31 and 34 were out of alignment, consequently the importance of having these ports in the axis of the cylinder and a rod common to both ports. Furthermore, it will be noted that the main 35 gasoline tank is constantly in communication with the upper end of the cylinder, thus obviating the use of check valves and the necessity of lifting the contents of the cylinder each and every time gasoline is drawn into the tank.

40 The simplicity of construction entering into the pump is such that the same is free from injury under ordinary conditions and does not require any attention after having been installed.

45 While in the drawing there is illustrated a preferred embodiment of the invention, it is to be understood that the structural

elements are susceptible to such changes, as 65 in the size, shape and manner of assemblage, as fall within the scope of the appended claims.

What I claim is:

1. The combination with a gasoline engine having a manifold, a carburetor communicating with the manifold of the engine, and a gasoline supply tank, of a cylinder having the upper end thereof constantly in communication with said gasoline supply 70 tank, said cylinder having an axial port in communication with the atmosphere and an axial port adapted to communicate with the manifold of said engine, whereby pressure can be reduced in said cylinder to cause 75 gasoline to flow from said supply tank in said cylinder, an auxiliary tank forming part of said cylinder and adapted to receive gasoline therefrom, a rod extending through both of said axial ports, and means on said 80 rod operable in said cylinder by the gasoline therein for alternately closing the axial ports of said cylinder to control the supply of gasoline to said cylinder and the passage 85 of gasoline from said cylinder to said auxiliary tank.

2. The combination with a gasoline engine having a manifold, a carburetor communicating with the manifold of the engine, and a gasoline supply tank, of a pump comprising a base, a cylinder carried thereby, an auxiliary tank supported by said base adapted to communicate with said cylinder and receive gasoline therefrom, a cap mounted upon said cylinder and having a 95 port constantly in communication with said gasoline supply tank, said cap having an axial port formed therein in communication with the atmosphere and an axial port adapted to communicate with the manifold 100 of said engine whereby pressure can be reduced in said cylinder to cause gasoline to flow from said supply tank into said cylinder, and vertically alining float actuated means within said cylinder adapted to alternately close the last mentioned ports of 105 said cap and control the supply of gasoline through said cylinder and through the auxiliary tank thereof.

3. The combination with a gasoline engine having a manifold, a carburetor communicating with the manifold of the engine, and a gasoline supply tank, of a cylinder having the upper end thereof constantly in communication with said gasoline supply 115 tank, said cylinder having an axial port in communication with the atmosphere and an axial port adapted to communicate with the manifold of said engine whereby pressure can be reduced in said cylinder to cause 120 gasoline to flow from said supply tank into said cylinder, an auxiliary tank in communication with the atmosphere and adapted to 125

communicate with said cylinder, and automatically actuated vertically alining valvular members movable in the same direction adapted to alternately close the axial ports of said cylinder and control the supply of gasoline to said cylinder and to the auxiliary tank thereof.

In testimony whereof I affix my signature in presence of two witnesses.

JOHN T. TRUMBLE.
